United States Patent Office.

ANSON P. THAYER, OF SYRACUSE, NEW YORK.

Letters Patent No. 78,401, dated May 26, 1868.

IMPROVEMENT IN MACHINE FOR GRINDING THE CUTTERS OF MOWING-MACHINES.

The Schedule referred to in these Letters Patent and making part of the same.

TO ALL WHOM IT MAY CONCERN:

Be it known that I, ANSON P. THAYER, of Syracuse, in the county of Onondaga, and State of New York, have invented a new and useful Improvement in Machines for Grinding the Cutters of Mowers and Harvesters; and I do hereby declare the following to be a full, clear, and exact description of the same.

The nature of my invention relates to improvements in portable machines for grinding the cutters of mowers and harvesters, similar to that patented by H. Whitall, May 14, 1867, and is for the purpose of rendering the same more simple, cheap, and effective. The machine may be readily carried by the hand into the field, and applied to the mowing-machine, to grind the cutters thereof, without taking them out of the machine.

And it consists in an arrangement of the operative parts upon a bench, which serves at the same time as the supporting-frame of the machine and a seat for the operator.

It also consists in an arrangement of means whereby the contact of the grinding-stone with the cutters is made yielding.

It also consists in an arrangement of the frame which supports the operative parts, in combination with the bench, whereby a firm and steady support for the swinging-frame is obtained.

It also consists in an arrangement of operative parts, hereinafter described, whereby the operator may apply the power of both hands to operate the stone.

It also consists in an arrangement of mechanism for adjusting the swinging-frame on its axis, and for connecting and disconnecting it to either side of the supporting-frame.

It also consists in the arrangement, with an oscillating-frame, of a feeding-screw that forms the axial support of the frame.

It also consists in the combination of a feeding-screw with the sliding-frame, and the grinding-wheel, and the operative mechanism, whereby it communicates reciprocating and rotary motion to the same; and

It also consists in the combinations and arrangements of the different parts, as will be more fully described on reference to the accompanying drawings, wherein—

Figure 1 represents a plan view of my improved machine, with a part broken away; it also shows some of the cutters of a mowing-machine in red; and

Figure 2 represents a side elevation of the same, with parts broken away.

Similar letters represent corresponding parts in both the figures.

A represents a bench made of wood, or any other suitable material, and provided with legs B, B¹, and B². C represents a metallic frame, provided with ears a a at each end, by which it is pivoted to the sleeves a¹ and a², and which constitutes the support for the operative parts. The sleeve a¹ is adjustable on the post B, and may be secured to it at any desired point by the screws by which the ears of the frame C are pivoted to it, which pass through the sleeve and sit against the post. The said frame is provided with a vertical and horizontal extension, C', which terminates in two curved branches for forming the bearings of a horizontal driving-shaft, C². It is also provided with another vertical extension, C³. Both these extensions pass upward through slots in the bench, whereby a firm and steady support is afforded against any tendency to a lateral trembling or vibrating action of the frame C, by reason of the action of the grinding-stone due to being suspended from one side of the frame D.

The sleeve a² is free to slide on the post B², which is provided with the adjustable rings b and b¹, and the spiral spring b². The ring b¹ is designed to prevent the sleeve from slipping off from the post, and must be set so low thereon that, when the latter stands upon the finger-bar of a mowing-machine, the grinding-wheel will be low enough to rest on the edge of the cutters, and be raised thereby slightly against the action of the spring b², the object of which is to produce an elastic and yielding pressure of the grinding-wheel on the said cutters, which is found for various reasons to be the best; as, for instance, the cutter-bar may sometimes spring in consequence of the pressure of the weight of the operator, or from the irregularity of such pressure due to the swaying motion of his body in operating the machine, and from various other causes.

The tension of the spring b^2 may be adjusted by the ring b , which may be adjusted on the shaft B^2 , and fixed at any desired point by a set-screw, whereby a uniform light or heavy pressure of the grinding-wheel on the cutters may be obtained. D represents an oscillating-frame composed of two cross-bars d and guide-rods d^1 , and suspended centrally on the screw-shaft E. F represents a sliding-frame, which is caused to move back and forth on the oscillating-frame D by means of a screw-thread on the shaft E working in a corresponding female thread in the hub f of the cross-bar of the sliding-frame F. The said frame supports the mandrel f^2 of the grinding-wheel G. g represents a driving-wheel connected to the sliding frame F by means of an annular projection on the cross-bar taking into an annular groove in the hub of the wheel, so as to cause the wheel to slide back and forth on the shaft with the frame F. The wheel g is provided with a spline, which takes into a long groove in the shaft, whereby rotary motion is communicated to the wheel, and by it to the bevel-pinion on the mandrel of the grinding-stone.

H represents a sleeve provided with a thumb-nut an internal screw-thread, and a swivel-joint at its upper end with a bent rod, which is connected to the horizontal bar of the frame C by a thumb-screw, h^2 . The lower end is connected to a screw-rod, h^1 , provided with an eye, which is slipped on to one of the guide-rods of the oscillating-frame D. By screwing the sleeve in one direction or the other, the frame D may be oscillated in either direction, and, by taking out the thumb-screw h^2 , the frame D may be turned over a half revolution, so as to present the grinding-wheel on the other side of the frame in the same relative position to it.

On the end of the screw-shaft E, next to the post B^1 , a bevel-wheel is fixed, which gears with a corresponding wheel on the vertical shaft I, which is supported at its lower end in a step in the frame C, and at its upper end passes through the bottom of the aforesaid branched upper termination of the frame C, and is provided on its upper end with a bevel-wheel, which gears into another similar wheel on the driving-shaft C², arranged in a horizontal position transversely of the bench, and is provided at each end with a hand-crank, in a suitable position for the operator's sitting on the bench, astride thereof, to take one crank in each hand, whereby he is enabled to exert his full power thereon, which is a matter of great importance in operating machines of this character, for the work is required to be done when time is of great value, which can be materially saved by this arrangement.

The red lines shown in fig. 1 represent a portion of the cutters and fingers of a mowing-machine.

To use my improved machine, the operator, having first moved the cutter-bar in the mowing-machine, so as to present one edge of all the cutters centrally between the fingers, as shown in fig. 1, places the foot of the post B^2 on the cutter-bar, and the legs B on the ground, taking care that the sliding-frame D stands on the line parallel with that edge of the cutter which stands between the fingers and is to be ground, and that the lower central portion of the stone is directly over the said edge of the cutters. Then, by means of the screwed sleeve H, he adjusts the oscillating-frame on the shaft E, so as to bring the lower face of the grinding-stone in an angular plane to agree with the bevelled face of the edge of the cutter. If, then, the ring b^1 , on the post B^2 , be adjusted low enough to allow the spring b^2 to bear the grinder on the said bevelled edge of the cutter, he sits down upon the seat A², and, by his weight thereon, maintains the post B^2 firmly in its position on the cutter-bar, while, with both hands applied to the cranks, he gives motion thereto and to the grinding-wheel, the rotation of which, in contact with the edge of the cutter at the same time that it is being reciprocated over the said cutting-edge by the screw E, grinds the same, as will be readily understood.

When the stone has traversed to the inner angle of the cutters, the operator turns the cranks in the other direction, and thereby moves it back again to the point, and repeats the operation until the cutter is sufficiently sharpened; after which, rising from his seat, he moves the machine along to the next cutter, and grinds it in the same manner, and continues the operation until all the cutters are ground on that edge. He then moves the cutter-bar, so as to present the other cutting-edges between the fingers in the same manner as before, when he raises the machine from the cutter-bar and disconnects the screw-sleeve H from the beam of the frame C, by taking out the thumb-nut h^2 , swings the oscillating-frame over, so as to present the grinding-wheel on the other side of the bench, when he applies the machine to the mowing-machine in the same manner as before stated, taking care that the oscillating-frame stands in a line parallel with that edge of the cutter, and that the grinder stands directly over the edge of the cutter; then, adjusting the oscillating-frame, so as to bring the lower face of the grinder to the same angular plane as that of the bevel of the edge of the cutter, he is ready to proceed to grind them on that edge, as before.

Having thus fully described my invention, what I claim, and desire to secure by Letters Patent, is—

1. A portable grinding-mechanism for grinding the cutters of mowing-machines, provided with a bench forming a seat for the operator, substantially as and for the purpose described.
2. A mowing-machine grinding-wheel provided with means for pressing it upon the cutter-blades with a yielding pressure, substantially as and for the purpose described.
3. The combination of the vertical extensions C¹ and C² of the frame C with the bench, substantially as and for the purpose described.
4. The mechanism of a portable cutter-grinding machine, constructed substantially as described, in combination with driving-mechanism arranged for the application of both hands of the operator to the driving-shaft, substantially as and for the purpose described.
5. The combination, with the frame C and the swinging-frame D, of the screwed sleeve H provided with a swivel-joint, substantially as and for the purpose described.
6. The combination of the oscillating-frame D with the feeding-screw E arranged within the frame, and serving as the axial support of the same, substantially as and for the purpose described.
7. The rotating feeding-screw, in combination with the sliding-frame, grinding-wheel, and its operative mechanism arranged with the screw, substantially as and for the purpose described.

8. The combination of the frame C with the adjustable sleeves a^1 and a^2 , posts B^1 and B^2 , and the bench A, substantially as and for the purpose described.

9. The combination of the frame C with the sleeve a^2 , post B^2 , provided with the spiral spring b^2 and adjustable rings b and b^1 , substantially as and for the purpose described.

10. The combination, with the frame C, of the crank-shaft C², vertical shaft I, and screw-shaft E, provided with the connecting-gear wheels, substantially as and for the purpose described.

In testimony whereof, I have subscribed my name, this 30th day of March, 1868.
